UNITED STATES PATENT OFFICE.

ALBERT W. ENGEL, OF CHICAGO, ILLINOIS.

ALBUM.

Application filed August 10, 1925. Serial No. 49,272.

The purpose of this invention is to provide an improved means for mounting pictures, clippings and the like particularly in a binder or album. It consists of certain features and elements of construction in combination as herein shown and described and as indicated by the claims.

In the drawings:—

Figure 1 is a face view of a sheet suitable for use as the leaf of an album constructed in accordance with this invention, and showing pictures mounted upon it by means of my improved system.

Figure 2 is a detail section on an enlarged scale taken substantially as indicated at line 2—2 on Figure 1.

Figure 3 is a detail section showing a part of the structure of Figure 2 on a still larger scale.

Figure 4 is a detail view showing a modified arrangement of the mounting means.

Figure 5 is a detail view illustrating another modification of the mounting means.

Figure 6 is a perspective view of a gummed fastener for use in accordance with this invention.

Figure 7 is a perspective view of an ornamental fastener of the type shown in Figure 4.

While my invention is shown as applied to an album leaf, it may be understood that many features of the invention may be used with any separate mounting sheet upon which pictures, clippings or the like are to be displayed. In Figure 1 the album leaf is indicated at 1 and is formed with a plurality of slits, 2, cut in various groupings and arrangements determined with a view to convenience and for adapting the leaf to serve

as a mount for pictures of various sizes. Some of the slits, 2, are shown as separate, while others are grouped in pairs either in T-shaped or crossed arrangement. Since most pictures are rectangular in outline, I have shown all the slits extending parallel to the sides or ends of the rectangular sheet, 1, but it may be understood that oblique arrangements of the slits would come within the scope of this invention.

Throughout the drawings a picture

(which may be in the nature of a photographic print) is indicated at 3 and the gummed paper fasteners by which the pictures are mounted are shown at 4. Each fastener is in the form of a short strip of material, gummed on one surface and folded at about the middle of its length, as seen in Figure 6. This strip is inserted in one of the slits, 2, with its line of fold substantially coinciding with the slit, so that one gummed leaf of the fastener is presented at one side of the sheet, 1, and the other leaf at the opposite side. The gummed surface is moistened and pressed into contact with the back side of the picture, 3, so that by the use of four or more of the fasteners a picture may be secured definitely in position on the album leaf, 1. In a similar manner another picture is secured to the opposite face of the leaf, 1, by attachment to the other halves of the fastener, 4, extending through the slits, 2.

In Figure 1 in the upper left hand corner of the album leaf, 1, I have shown a picture secured by means of five fasteners, 4, so that a pocket is formed between the picture, 3, and the leaf, 1, the middle fastener, 4, at the lower edge of the picture forming a bottom for the pocket, and the pocket being upwardly open along the upper edge, 5, of the picture. For photographic work this provides a very convenient pocket for holding the negative film from which the print, 3, has been made, while the print itself readily identifies the negative. This method of use is found illustrated in the sectional views at Figures 2 and 3 in which negatives A and B are shown mounted in pockets at both sides of the album leaf, 1, under their respective prints, 3 and 3^a. These sectional views clearly indicate the interlocking of the fasteners, 4, with the sheet, 1, by their engagement in the slits, 2, of the sheet.

In the upper right hand corner of Figure 1 I have illustrated the use of an ornamental mount or mat for a picture, such mat being shown at 6 as a sheet of mounting material slightly larger in area than the picture, 3, and having slits which register with the corners of the picture, so that the fasteners, 4, extend through these slits as well as

through slits, 2, in the album leaf, 1. This mat sheet, 6, is included in the sectional views in Figures 2 and 3.

As a modified form of fastener Figure 7 shows a device, 7, which may be cut in ornamental form, as with one diagonal edge and projecting tabs, 7^a, and which is folded so that its gummed surfaces face inwardly instead of outwardly. This type of fastener is also used with my improved album leaf by inserting it through one of the slits, 2, as shown in Figure 4, and also in the lower left hand corner of Figure 1. The gummed surface of the fastener will, of course, adhere to the outer surface of the picture at its corner and may also be secured to the face of the sheet 1. The tabs, 7^a, may be tucked under the edges of the picture, as shown in Figure 4, or may be lapped over these edges, as shown in Figure 1 with the corner of the picture itself overlapping the diagonal edge of the fastener. Or, if preferred, the fastener may be cut in the form shown in Figure 5 without any projecting tabs but merely having an oblique or diagonal edge giving an ornamental effect when the picture, 3, is secured to the leaf, 1, with the fastener overlapping the picture. If desired the fastener may be rendered less conspicuous by making it of transparent material such as celluloid so that the picture will show through it as indicated in Figure 5.

I claim:—

1. The combination of a mounting sheet formed with a slit, a sheet to be mounted, and a fastener of sheet material, gummed on one surface and folded, engaged in the slit with its line of fold substantially co-incident therewith and with its gummed surface at one side of the fold secured to the sheet to be mounted.

2. In the combination defined in claim 1, the portion of the fastener at the other side of its fold being presented through the slit at the other side of the mount for attachment to a second sheet to be mounted.

3. In the combination defined in claim 1, the folded fastener being gummed only on one surface and set in the slit with its gummed surface facing outward away from the mount.

4. The combination of a mounting sheet formed with a plurality of slits, fasteners of sheet material each gummed on only one surface and folded and each engaged in one of the slits with its line of fold substantially co-incident therewith and with its gummed surface facing outward away from the mount, and a sheet to be mounted secured to the outwardly facing gummed surface of said fasteners and retained in position by the engagement of said fasteners and the slits.

5. In the combination defined in claim 4, the slits in which said fasteners are engaged

being disposed in line with a plurality of adjacent edges of the sheet to be mounted but leaving at least one edge of said sheet without such fasteners whereby the mounted sheet forms a pocket on the mount open at 70 the unattached edge.

6. In the combination defined in claim 4, the sheet to be mounted being rectangular and the slits in which the fasteners are engaged being disposed adjacent three edges thereof, whereby a fourth edge is left unattached to the mount to provide a pocket behind the sheet which is mounted thereon.

7. The combination of a mounting sheet formed with a plurality of slits, fasteners of sheet material, each gummed on only one surface and folded, each engaged in one of the slits with its line of fold substantially co-incident therewith and with its gummed areas at opposite sides of the fold, facing 85 outwardly away from the opposite sides of the mounting sheet respectively, together with two sheets to be mounted, one secured to the gummed surfaces of the fasteners at one side of the mounting sheet and the other secured to the gummed surface presented at the other side of said sheet.

8. In the combination defined in claim 7, said sheets to be mounted being rectangular and the slits engaged by the fasteners being 95 all disposed adjacent three edges of said sheet, whereby a fourth edge of each sheet is left unattached to form a pocket.

9. The combination of a mounting sheet formed with a plurality of slits arranged in spaced relation to each other in parallel rows, a sheet to be mounted and a plurality of fasteners of sheet material, each gummed on one surface and folded, engaged in the slits with their lines of fold substantially co-incident therewith and with their gummed surfaces secured to the sheet to be mounted.

10. The combination of a mounting sheet formed with a plurality of slits in parallel rows and additional slits perpendicular thereto, and fasteners of sheet material each gummed on one surface and folded, adapted for insertion in the slits, each with its line of fold substantially co-incident with a slit for presenting a gummed surface at either side of the mounting sheet to secure a sheet to be mounted.

11. In combination with a mounting sheet formed with a slit and a sheet to be mounted, a fastener in the form of a strip of sheet material whose width is substantially equal to the length of the slit, said strip being gummed on one side and folded transversely between its ends whereby it may be entered in the slit with its lateral edges checked by the ends of the slit and with its line of fold substantially co-incident therewith, presenting gummed surfaces at both sides of the mounting sheet for attachment to a sheet to be mounted thereon.

12. The combination of a mounting sheet formed with a slit, a sheet to be mounted, and a fastener of sheet material gummed on one surface and folded, engaged in the slit with its line of fold substantially coincident therewith, the gummed surface of the fastener at one side of the fold being secured to the sheet to be mounted and being secured to a piece of sheet material at the other side of the fold, whereby it is anchored in the ¹⁰ slit.

In testimony whereof, I have hereunto set my hand at Chicago, Illinois, this 21 day of November, 1923.

ALBERT W. ENGEL.
